UNITED STATES PATENT OFFICE.

ARTHUR WHITE, OF SHEBOYGAN FALLS, WISCONSIN.

DRY-KILN.

No. 888,227.

Specification of Letters Patent.

Patented Dec. 11, 1906.

Application filed March 28, 1906. Serial No. 308,018.

To all whom it may concern:

Be it known that I, ARTHUR WHITE, residing in Sheboygan Falls, in the county of Sheboygan and State of Wisconsin, have invented new and useful Improvements in Dry-Kilns, of which the following is a description, reference being had to the accompanying drawings, which are a part of this specification.

10 This invention relates to dry-kilns, and has for its object to provide a dry-kiln of fire-proof construction throughout.

Another object of this invention is to provide a dry-kiln of novel construction where-
15 by the moist hot air on leaving the lumber or other material being dried is carried into contact with a condensing-surface formed by a sheet-metal roof and after having the moisture abstracted therefrom by condensation is returned to the heating apparatus to again pass around the material being operated upon.

Another object of this invention is to provide such a dry-kiln with means for adjust-
25 ably limiting the air-passages so that the air circulation may be controlled and to enable the air being confined within the drying-chamber without circulation at the beginning of the drying operation, whereby the
30 material operated upon may be thoroughly heated through, so that later on when circulation is established the drying operation will take place throughout the material instead of at the surface only.

35 Another object of this invention is to provide means for artificially cooling the condensing-surface formed by the roof during warm weather.

Another object of this invention is to im-
40 prove upon details of construction of a dry-
kiln of this type to render it more efficient in its operation.

With the above and other objects in view the invention consists in the dry-kiln herein
45 claimed, its parts and combinations of parts, and all equivalents.

Referring to the accompanying drawings, in which like characters of reference indicate the same parts in both views, Figure 1
50 is a transverse sectional view of a dry-kiln constructed in accordance with this invention; and Fig. 2 is a longitudinal sectional view thereof, taken on the plane of line 2-2 of Fig. 1, the line 1-1 of Fig. 2 indicating the
55 sectional planes of Fig. 1.

In the drawings, 5 represents the upright

walls, preferably of cement construction, which inclose the substantially rectangular drying-chamber, which is sealed at the bottom by a cement flooring 6 to prevent the waste of energy in drawing moisture from the ground beneath and which is covered by an inclined roof 7, of thin sheet metal, to form a condensing-surface, as will be later explained. The sheet-metal roofing is supported by a network of T-rails 8, which extend longitudinally and transversely of the drying-chamber with their flanges interlocking, and at intervals the sheet-metal covering forms upstanding ridges by being clamped upon the upwardly-extending flanges of parallel T-rails 9, resting upon this network and extending longitudinally of the drying-chamber.

At the front end of the drying-chamber is located a door 10, which controls the only opening to the interior, and through the doorway a pair of trucks 11, containing lumber 12 or other material to be dried, may enter on tracks 13, which are supported some distance above the floor on cement pillars 14. In the spaces between the pillars 14 and beneath the trucks are located series of heating-coils 15, supplied with steam by steam-pipes 16, which extend transversely through the drying-chamber, so as to be common to other drying-chambers arranged alongside of the one shown in event of the construction being in multiple, as is usual.

Some distance below the roof 8 and parallel with it extends an I-beam 17 down the middle of the drying-chamber and directly above the space between the two trucks of lumber. This I-beam is supported at its ends upon ledges 18, which project inwardly from the front and rear walls of the drying-chamber and extend from side to side thereof. Cross-beams 19 connect with the I-beam 17 and extend from one side of the drying-chamber to the other. A sheet-metal partition-plate 20 is located along each side wall of the drying-chamber at a short distance therefrom to form a return-passage therebetween and extends from the front wall to the rear wall of the drying-chamber and from brackets 21 a short distance above the floor and below the heating-coils 15 to the level of the I-beam 17. At the upper end of each partition is an inclined cover member 22, which extends over the truck of lumber on that side of the drying-chamber to near the I-beam, being bent to form a

trough-like cover for the truck of lumber and supported by the cross-bars 19. The covers are adapted to convey water of condensation to the rear ledge 18, which is provided with a 5 gutter and spout 23, leading through the rear wall and terminating in a trap or water seal 24.

The I-beam 17 is provided with a sheet-metal cap 25, which extends along it from 10 end to end, with the edges outstretched toward the overhanging covers 22. To these edges are hinged curved flaps 26, which are adapted to overlap the edge of the covers 22 and are capable of swinging to increase or 15 diminish the spaces between them and the edges of the covers 22. Similarly-arranged flaps 27 are hinged to the side walls of the drying-chamber to overlap the outer edges of the covers 22, and they may also swing to 20 vary the spaces between them and the covers. A rock-shaft 28 extends across the drying-chamber beneath the I-beam 17, with its ends passing through the partition-plates 20 and journaled in the side walls of the drying- 25 chamber, and arms 29 extend upwardly and forwardly therefrom, with rollers on their ends to ride upon the hinged flaps 26 and 27. A crank-arm 30 is connected with the rock-shaft 28 at its middle portion and is pivotally connected to a handle-rod 31, passing 30 through an opening in a standard 32, which is rigidly supported from the floor, the handle-rod being provided with teeth on its under edge to engage the standard and hold the 35 rock-shaft in its various adjustments. By pulling forwardly on the handle-rod 31 the rock-shaft is caused to turn so as to lift the arms 29, and they in turn swing the flaps 26 and 27 upwardly to open the passages between them and the covers 22. The rearward 40 movement of the handle-rod 31 causes the rock-shaft to swing in the opposite direction and allows the flaps to drop to a closed position in engagement with the edges of the 45 covers 22 to close the passages.

When it is desired to provide for cooling the sheet-metal roof 7 by artificial means, a series of spray-pipes 33 are supported above the roof and are supplied with cold water under pressure from a pipe 34, the water being sprayed through perforations of the spray-pipes over the entire surface of the roof, thus cooling the thin sheet metal forming the condensing-surface and facilitating the condensing operation. Besides the cooling effect produced by bringing cool water in contact with the sheet metal of the condensing-surface evaporation of moisture on the roof will act to increase the cooling effect and materially assist in the condensation.

In operation a pair of trucks of lumber or other material to be dried are run into the kiln through the open doors 10 and upon the rails 13, the handle-rod 30 is pushed to the rear, so as to close all of the passages con-

trolled by flaps 26 and 27, the doors are closed tightly, and the spaces between the doors and rails are filled in in any desirable manner, so as to tightly seal the entire drying-chamber. Now steam is admitted to 70 the heating-coils 15 and the drying-chamber is kept at a high temperature for a sufficient length of time to enable the lumber or other material becoming heated throughout, and during this heating operation there is no circulation of air, so that the air within the drying-chamber remains moist and there is no surface-drying of the material produced. If circulation should be allowed at the start, it would tend to dry out and contract the pores 75 of the surface of the wood before the inner portion had become sufficiently warm to expel its moisture; but by preventing the circulation and keeping the air around the wood moist the surface-pores are kept open, 80 so that as the heart of the wood becomes heated its moisture may be freely expelled. This condition of the apparatus is maintained for twenty-four hours or so, and then the handle-rod 31 is drawn forwardly to open 85 the flaps 26 and 27 to the desired extent. This will allow the moist air within the drying-chamber to pass out through the openings between flaps 26 and the covers 22 into the condensing-space between the covers and 90 the roof. The air being warm will rise to the surface of the sheet-metal roof 7, which is kept cool by the outer atmosphere or by the artificial cooling means, so that the moisture of the air will become condensed and will 95 drop to the trough-shaped covers 22 or to the other parts, which are all so shaped as to constitute troughs leading to the gutter in the rear ledge 18, whereby the water of condensation is all collected in said gutter and discharged through the rear wall. After the air has become dry in this manner it passes 100 down through the openings beneath the flaps 27 and into the return-passages formed between the partition-plates 20 and the side 105 walls to the spaces beneath the heating-coils 15, where it is reheated to pass up through the lumber again and abstract more moisture therefrom and continue this cycle of operation until the end of the drying process, 110 all moisture taken from the wood being condensed and discharged from the kiln in the manner set forth.

Obviously the adjustments of the flaps may be accomplished in any other desirable 115 manner without departing from the spirit and scope of this invention. Likewise other details of construction may be modified or departed from without affecting the invention.

By reheating the same air over and over again and condensing the moisture therefrom the drying operation is made much more economical than when the moist air is discharged directly to the atmosphere and 120

fresh air taken in from the outside is required to be brought from the atmospheric temperature to the drying temperature.

What I claim as my invention is—

- 5 1. In a dry-kiln, a drying-chamber, a roof covering the drying-chamber comprising a network of T-rails extending across each other with their flanges interlocked, and a sheet-metal covering supported by the framework, there being passage-ways leading to and from the roof through which the moisture-laden air from the drying-chamber may pass to produce condensation of the moisture.
- 15 2. In a dry-kiln, a drying-chamber, a roof covering the drying-chamber comprising a net-work of T-rails extending across each other with their flanges interlocked, a series of parallel T-rails supported by the network, and a sheet-metal covering turned over the flanges of the parallel T-rails, there being passages leading to and from the roof through which the moisture-laden air from the drying-chamber may pass to produce condensation of the moisture.
- 25 3. A dry-kiln, comprising a drying-chamber, a roof forming a condensing-surface, a cover between the drying-chamber and the roof with a condensing-space above it, a return-passage leading from the condensing-space to the drying-chamber, and means for controlling communication between the drying-chamber and the condensing-space.
- 35 4. A dry-kiln, comprising a drying-chamber, a roof forming a condensing-surface, a cover between the drying-chamber and the roof with a condensing-space above it, a return-passage leading from the condensing-space to the drying-chamber, means for controlling communication between the drying-chamber and the condensing-space and between the condensing-space and the return-passage, and mechanism for operating the controlling means.
- 45 5. In a dry-kiln, walls containing a drying-chamber, a partition between one of the walls and the drying-chamber forming a return-passage, a cover for the drying-chamber connecting with the partition, a roof comprising a condensing-surface above the cover with a condensing-space therebetween, a hinged flap for closing communication between the drying-chamber and the condensing-space, a hinged flap for controlling communication between the condensing-space and the return-passage, and means for moving the flaps.
- 55 6. In a dry-kiln, walls inclosing a drying-chamber, partitions spaced from opposite walls to form return-passages therebetween, covers for the drying-chamber connecting with the partitions and terminating at a distance from each other, a support extending between the covers, flaps hinged thereto and adapted to close the space between the covers, hinged flaps adapted to close the return-passages, a roof constituting a condensing-surface above the covers, and means for moving the flaps.
7. In a dry-kiln, walls inclosing a drying-chamber, partitions spaced from opposite side walls to form return-passages, inclined covers for the drying-chamber connecting with the partitions and terminating at a distance from each other, ledges on the front and rear walls at different elevations, a beam supported on the ledges and lying in the space between the edges of the covers, hinged flaps carried by the beam and adapted to close the space between the covers, hinged flaps adapted to close the return-passages, a roof forming a condensing-surface above the covers, a rock-shaft journaled across the drying-chamber, means carried by the rock-shaft and bearing on the flaps, a crank-arm connected with the rock-shaft, a handle-rod connected with the crank-rod, a support for the handle-rod, and teeth carried by the handle-rod for locking the rod in its adjustments by engaging the support whereby the flaps may be held more or less open for the circulation of air for condensation.
8. In a dry-kiln, walls inclosing a drying-chamber, partitions spaced from opposite side walls to form return-passages, inclined covers for the drying-chamber connecting with the partitions and terminating at a distance from each other, ledges on the front and rear walls at different elevations, a beam supported on the ledges and lying in the space between the edges of the covers, hinged flaps carried by the beam and adapted to close the space between the covers, hinged flaps adapted to close the return-passages, said covers and flaps being curved to form troughs leading to the ledge on the rear wall, said ledge being provided with a gutter and spout to discharge water of condensation through the wall, a roof forming a condensing-surface above the covers, a rock-shaft journaled across the drying-chamber, arms carried by the rock-shaft and bearing on the flaps, and means for turning the rock-shaft to open and close the flaps for controlling the circulation of air for condensation.

In testimony whereof I affix my signature in presence of two witnesses.

ARTHUR WHITE.
